ABSTRACT OF THE DISCLOSURE

Certain fluorocarbon quaternary salts, a process for their preparation and compositions containing the salts are disclosed. These salts are shown to have antimicrobial properties.

BRIEF SUMMARY OF THE INVENTION

This invention relates to antimicrobial (e.g. antibacterial and antifungal) substances and to compositions containing them. More particularly, it relates to fluorocarbon quaternary salts and compositions thereof.

Various quaternary salts are known to be useful and active antimicrobials. Certain fluorocarbon quaternary salts have also been known previously e.g., (see U.S. Patents 2,727,923, 2,759,019, 2,764,602 and 2,764,603). These have been shown to be surface active compounds with unusual properties, but their use as antimicrobials has not been disclosed. Indeed, the fluorocarbon quaternary salts, particularly those with larger fluorocarbon groups (e.g. above C_2F_5), would be expected to have little or no antimicrobial activity since such fluorocarbon groups normally reduce or obviate pharmaceutical activity. The present invention relates to a novel class of fluorocarbon quaternary salts (containing relatively large fluorocarbon groups) which are not only unexpectedly active antimicrobials, but which, as will be shown, are much safer for certain applications than previously known quaternary antimicrobials.

It is an object of the present invention to provide a novel class of quaternary compounds.

It is another object of the present invention to provide novel antimicrobial compositions comprising certain new fluorocarbon quaternary compounds in a pharmaceutical medium.

It is another object of the invention to provide a new method of combatting microbes comprising contracting them with a fluorocarbon quaternary compound.

Still other objects of the invention will become apparent to those skilled in the art from the following detailed description.

DETAILED DESCRIPTION

In accordance with the various aims and concepts of the present invention, there are provided fluorocarbon substituted quaternary compounds of the formula:

wherein m is 5-7. These compounds are conveniently prepared by treating pyridine with an alkylating agent, such as

in an inert solvent, usually at an elevated temperature.

The high degree of safety of the compounds of the invention as antimicrobials is of major importance in various areas of use. An example of this is topical application to wounds of domestic animals or pets. Since the wounded area is likely to be licked by the animal, it is important that the antimicrobial be as non-toxic as possible while

2

still retaining its effectiveness. Another area in which safety is important is in oral antiseptics such as mouth washes.

The relative safety of compounds for therapeutic uses is commonly measured as a Therapeutic Index, i.e. the ratio of effectiveness to lethality. In the present case, this can be measured as the ratio of the effectiveness against microorganisms to the lethality against test animals.

As antimicrobial agents, the compounds of this invention may be applied directly and alone to the tissue or material to be treated or conventional carriers or diluents may be incorporated with them before application. The choice of carrier or diluent and the concentration of the active ingredient are determined by the use of the composition.

For treatment of topical infections in mammals, e.g. in dogs or other domestic animals, the compositions are usefully employed as ointments which are not readily removed from the treated area by movement or rubbing. Other pharmaceutical carriers which can be used are organic solvents (such as alcohols, e.g. ethyl alcohol), water (to dissolve or suspend the active ingredient), solid inert materials such as talc, bentonite, kieselguhr, diatomaceous earth, and the like, emulsifying agents, etc. The fluorocarbon quaternary salts of the invention can also be dispersed in pressure sensitive adhesives for use in surgical tapes, drapes, etc. In such cases, the adhesives can also be considered to be pharmaceutical extending media.

The following will illustrate the preparation of the compositions of the invention and their antimicrobial effectiveness.

1,1 - dihydroperfluoroctyl trifluoromethanesulfonate (5.3 g., 0.010 mole) was added dropwise to a stirred solution of 1.8 g. (0.022 mole) of pyridine in 100 ml. 2-butanone at reflux temperature. After heating for an additional two days, the mixture was concentrated to dryness. The oily residue was triturated with ether to afford a solid which was collected and recrystallized twice from chloroform to afford 1.4 g. (23%) of N-(1,1-dihydroperfluoroctyl)pyridinium trifluoromethanesulfonate having the structure:

The melting point of this compound was 110-111.5° and the results of analytical tests thereon were as follows:

Calc'd for $\text{C}_{13}\text{H}_7\text{F}_{15}\text{N}\cdot\text{CF}_3\text{O}_3\text{S}$: C, 27.5; H, 1.5. Found: C, 27.6; H, 1.3.

The 1,1 - dihydroperfluoroctyl trifluoromethanesulfonate used in the foregoing preparation was prepared according to the method described by Hensen (J. Org. Chem., vol. 30, p. 4322, 1965) utilizing 1,1-dihydroperfluoroctyl alcohol.

The effectiveness of the perfluoroctyl pyridinium salt as an antimicrobial was evaluated against four bacteria (*Staphylococcus aureus*, *Streptococcus* sp. 104 *Escherichio coli* and *Bacillus subtilis*) and two fungi (*Aspergillus niger* and *Candida albicans*) using a variation of the agar plate diffusion method of Vincent and Vincent (Proc. Soc. Expt. Biol. Med. 55: 162-164) using culture media based on the synthetic glucose-salts medium of Davis and Mingoli (Jour. Bact. 66: 129-136). Both serum free cultures and cultures with serum or blood were tested with each microorganism. For purposes of comparison an identical set of tests were run utilizing the well known and highly active antimicrobial compound cetyl pyridinium chloride (ref. The Merck Index of Chemicals and Drugs, Published by Merck and Co., Inc., Rahway, N.J., Seventh Edition, 1960, p. 227). The perfluoroctyl pyridinium salt was found to be significantly more active against the bacteria than the cetylpyridinium chloride and slightly less active against the fungi.

Comparing the same two compounds as to their acute toxicity in rats it was found that the LD₅₀ (oral) of the perfluoroctyl pyridinium salt is 1159 mg./kg. and that the LD₅₀ (oral) of the cetylpyridinium chloride is 538 mg./kg. Thus the effective safety (Therapeutic Index) of the perfluoroctyl pyridinium salt is very significantly greater than that of the cetylpyridinium chloride against both bacterial and fungi, particularly the former.

What is claimed is:

1. A quaternary compound of the formula:

wherein m is 5-7.

2. A compound according to claim 1 wherein m is 6.
